METHOD OF MAKING MATTRESSES, CUSHIONS, UPHOLSTERY, HEAT AND SOUND INSULATING COVERINGS AND THE LIKE

Karl Hermann Hackländer, Vaduz, Liechtenstein, assignor to Agricola Reg. Trust, Vaduz, Liechtenstein

Application February 2, 1956, Serial No. 589,352

Claims priority, application Great Britain February 3, 1955

8 Claims. (Cl. 154—106)

This invention relates to mattresses, cushions, upholstery, heat and sound insulating coverings and the like.

The invention is concerned with the use of the resilient heat and sound insulating and absorbing properties of that class of flexible plastics which is resilient due to the presence throughout the material of pores, generally known as resilient expanded plastic. One example of such a material is expanded polyurethane, sold under the name "Moltopren." Such material may be made in a variety of textures, from highly porous and very springy to very soft and having little porosity, as well as in the form of flakes, granules, chips and shreds which may be used for the filling of upholstery.

It is well known to use a thick sheet of a resilient expanded plastic as a mattress, for example, but full benefit of the properties is not obtained as the material spreads, and, as it were, flows away from under the load. Similarly, in the case of a seat cushion, the material in the thickness of the cushion moves radially, and in order to adequately support the weight a greater thickness of material is required than would be the case if such radial movement did not take place. Clearly such flow of the material will not take place in the case where the area of the load is the same as the area of the resilient material and the material is confined around its edges, but of course, this is not practical in the case of mattresses, cushions and most forms of upholstery.

It is the object of the invention to overcome the disadvantages above referred to.

The invention consists in a mattress, cushion, upholstery and such like constructed in part at least of resilient expanded plastic characterised in that in the absence of a load, the material adjacent the intended area of contact with the load is under tension in a direction transversely of the direction of the load, while material remote from said area is under compression in a direction transversely of the direction of the load.

The accompanying drawings show, by way of example only, a number of embodiments of the invention the characteristics of which will be apparent from the following description.

In the simplest form of construction comprising a circular cushion for use on the seat of a chair, and constructed in accordance with the invention, is obtained when as shown in section in Figure 1 and plan in Figure 1a a single sheet 1 of the resilient expanded plastic is used say of 3 or 4 inches in thickness, the material is laid upon a flat table 2 and compressed by means of a circular shaped member 3 laid thereon approximately the size of the cushion required and when the material has been compressed say to $\frac{1}{4}$ inch in thickness it is welded around the edge of the upper member by means of a shaped heated tool or a wheel or other known method so that the pores are removed entirely along this line and upon removing of the upper member the sheet of material returns approximately to its original thickness as shown in Figure 2 in side elevation but is constrained around the periphery of the cushion. The surplus material is then trimmed away

2

from the outside of the weld as shown in Figure 3. It will be understood that in the action of returning to its original thickness the material towards the outer surfaces of the cushion becomes under tension while the material along the plane of the centre of the cushion becomes compressed so that when a load is placed upon the cushion the action is to prevent the material from flowing radially away from under the load.

In another form of construction as shown in Figure 4 of a similar cushion three layers of sheet material are placed one upon the other before being compressed and welded, the materials 4 on the outer surfaces of the sandwich being particularly chosen to resist stretching under the tension produced, while the material 5 in the centre 15 of the sandwich is chosen to resist compression under stressing. The materials which are suitable in this case may also be suitable for the other purposes they serve, for example, the outer members 4 of the sandwich shown in Figure 5 may have a closer texture and form a suitable 20 surface to prevent wear and slipping, while the inner sandwich 6 may consist of loose granules, flakes, chips and such like or reconstituted sheets of flakes or scrap materials which are bound together, e. g. by adhesives or by the application of a moderate heat, that is, insufficient 25 to melt the material.

In a still further alternative form of construction of this simple form of cushion as shown in Figure 6 the outer layers 4 of the sandwich may be formed of resilient expanded plastic while the inner layer 7 of the sandwich 30 may be of rubberised hair or other well known suitable resilient upholstering material which will withstand the compressing forces exerted by the stretching of the outer layers during the compression of the cushion.

In the last form of construction clearly the cushion 35 cannot be compressed to the same degree when the central layer of the sandwich is not particularly resilient as is the case with the expanded plastic, and it may be necessary to apply stretching forces as shown by the arrows to the outer layers while the cushion is being compressed 40 in order to ensure that adequate tensional forces remain in the outer layers after the welding process has been completed.

Where, however, for example, a highly porous plastic filling is required for the sandwich, as when used say 45 in a cinema seat, the said material may be provided with a number of perforations extending through the inner layer 8 as shown in Figure 7 which are closed at their ends either by the outer layers of the sandwich or by the seat structure and which thus form closed voids in the 50 thickness of the seat.

Where it is required to provide a considerable resistance to a load a cushion or mattress can be constructed of a sandwich of three or more sheets of material as shown in Figure 8 in which each of the sheets can be of progressively increasing (or decreasing) resilience through the 55 article. Such a construction will give considerable resilience where the load is light while the resilience will progressively decrease with increase of the load.

Although it is preferred to attach the layers of the 60 sandwich together by welding, as it is a quicker and simpler process and a thermoplastic material must be employed, it is also within the scope of the invention to attach the layers of the sandwich to one another around the periphery of the cushion as shown in Figure 9 by 65 means of sewing, by clips, staples or by any other suitable means as desired.

To summarise therefore the simple form of construction so far described, the cushion may consist of a single 70 layer of resilient expanded plastic having imparted to it during the manufacturing process tensional forces at and near the surfaces and compressional forces around the mid plane, the surfaces being brought into close juxtap-

position by welding, sewing or other means of fixing around the periphery so that said forces are produced and exist in the cushion until such time as a load is applied to the same. The nature of the cushion may vary through its cross section for example by forming a sandwich so that the material adjacent the surfaces is chosen to resist tensional forces while the material between is chosen to resist compressional forces.

It will be understood that the extent and the disposition of forces throughout the cushion depend on the relationship between the diameter of the cushion and the overall thickness of the same and that should the cushion be thin as compared with its diameter forces will be only relatively slight at the centre and it is therefore proposed in accordance with the invention to weld the material through its thickness and between the surfaces at, for example, a point in the centre of a circular cushion as shown in Figure 10 thereby producing a further anchor-point 9 from which the tensional and compressional forces may radiate. This anchor-point may be produced by the method first referred to, namely compressing the material between parallel plates and welding through a hole 10 provided in the centre of the circular top plate 11.

It is within the scope of the invention to so design the compression plate above referred to such that portions of the plate are raised in relation to the remainder as shown in Figure 11 and form heating electrodes by which the welding is carried out upon the surface of a table 2 below or upon electrodes 12 formed on a further plate 13 below as shown in Figure 12 so that a symmetrical arrangement is obtained.

Furthermore, a pattern may be embossed upon the surface of the cushion or the like by projections upon the compressing plate or a further plate provided for this purpose as shown in Figure 13.

When a structure such as a mattress is required where the dimensions across the sheet of material are much greater than the thickness thereof many anchor-points 9 may be provided throughout the surfaces as shown in Figure 14 so that adequate stresses are incorporated in the structure and the tendency for the material to flow under the load imposed thereon is adequately resisted. These anchor-points may be formed at regular or irregular distances apart from one another so as to produce an interesting pattern upon the mattress.

In a still further alternative form of construction, besides the mattress being welded around its edges by straight or curved lines, anchorage may be provided within the area of the surfaces by straight or curved lines either in addition to the anchor-points or alternative thereto, for example to form straight ribs from side to side or from end to end of the mattress as in a quilt or in a lattice pattern as shown in Figures 14 and 15.

The mattress, cushion, upholstery and the like may be constructed of a single sheet-like layer or three sheet-like layers to form a sandwich as above referred to, or an odd number of layers where the structure is required to be handled independently of any rigid structure to which it may be temporarily or permanently attached, whereby the forces within the material are symmetrical about a mid-plane, but where the structure is to be fixed to a rigid backing, for example the back or seat of a chair, an even number of layers may be provided, for example two, in which the outer layer retains the tensional stresses while the inner layer retains the compressional stresses, the upholstery being prevented from rolling up by direct or indirect attachment to the rigid backing.

Alternatively, as shown in Figure 16, the structure may be constructed of a single thin layer of material which normally would be symmetrical after welding and therefore have tensional stresses at and near the surfaces and compressional stresses between and then be attached around its edge to a flat rigid surface 14 such as plywood in which the action of attachment will increase the ten-

sional stresses at the outer surface as shown by the arrows and transfer the compressional stresses from the middle of the structure to the surface adjacent the backing. Such treatment of the structure then converts the upholstery from a symmetrical arrangement to a non-symmetrical arrangement. Such a structure also is within the scope of the invention.

In order that there shall be adequate material for attachment to a backing either in the above or any other form of construction the weld may be made that much wider and so produce a flange around the article as shown in Figure 17 or two separate welds may be made the one adjacent the other for the same purpose.

Seeing that when a mattress or cushion is constructed in accordance with one method of carrying the invention into effect by the application of pressure between parallel surfaces while the welding process is being carried out and tensional and compressional forces are not existent at this time, it can be clearly understood that when a load is applied to such a mattress or cushion which covers substantially the whole of the surface during use the tension and compression forces are relieved, and the resilience of the material supports the load wholly normally to the surfaces thereof and transverse flow of the material is eliminated.

Where for any reason it is inconvenient to provide a press large enough to accommodate a mattress or any substantial area of material which it is required to make up in accordance with the invention, a sandwich may be formed and the outer surfaces of material be attached to means for stretching it in its own plane as shown by the arrows in Figure 18 without compressing between parallel surfaces and before the welding or sewing is carried out around the periphery. The welding may be then effected by means of a smaller heated hand wheel which may be caused to follow a curved path to a particular design and at the same time or subsequently anchor-points or anchor-lines may be introduced independently by hand as and where required to join the front and back surfaces together. It can therefore be seen that the invention is not limited to the method of compression between parallel surfaces although this method is found to be most effective as the work can be carried out more rapidly by this means.

Where it is required for the finished product to have a corrugated or waved or other shape imparted to it as shown in Fig. 19, the surfaces between which the sandwich or single layer is compressed may be curved or shaped and consequently the method of compression during the welding process is not limited to flat parallel plates. For example, where a mattress is required for heat insulating or sound insulating or absorbing purposes and is required to cover a semispherical surface the compressing surfaces may be suitably shaped so that the finished product is of the desired curvature.

The method and product in accordance with the invention is particularly applicable to use with upholstery covering large surfaces such as aeroplane seats, divans, and the like, while the curved or cylindrical parts required may be formed during the forming of the main load carrying surfaces of the seat and back as shown in Figure 20, the whole structure being attached to a flat backing either along the lines of the welds or by adhesive with the whole of the back.

Sheets of material formed in accordance with the invention are particularly useful for lining walls, ceilings, etc. for heat insulating and sound insulating and absorbing purposes and can be constructed by a continuous process in which pressure is applied to the single sheet or the sandwich of material by a roller or a system of rollers 17 and 18 as shown in Figure 21 while the welds are applied simultaneously in a similar manner by the electrodes 12. Such a material may be con-

veniently attached to the backing along the lines of the welds.

Where desired, a decorative or wear-resisting fabric 15 may be placed on the surface of the single sheet or sandwich as shown in Figure 22 during the forming process and, if of a thermoplastic nature, becomes attached to the final mattress, cushion or upholstery along the lines of the welds 16 and becomes incorporated in the final product, and due to the compressing process is held stretched between the welds by the resilient action of the layer or layers when released from the pressure.

Where the mattress, cushion, upholstery or the like is used for the purpose of supporting the human body it is preferable that the material be of the kind in which the pores are interconnected so that the material may "breathe" and condensation be prevented from forming, but when such use is not made of the structures the material in which the pores are not interconnected can also be used satisfactorily.

Small cushions or pads constructed in accordance with the invention may be employed as cleaning pads for motor vehicles and the like in which a hose is fixed into a recess in the material and is welded closely around the same, so that water issuing from the hose emerges by way of the pores in the material over the surface of the pad. Also an earphone or a small loud-speaker may be inserted in a cushion before it is welded, such a cushion being of particular use in hospitals and such institutions.

In a still further construction in accordance with the invention, fabric membranes, e. g. a net extensible in all directions, may be incorporated in the sandwich to resist the overall stretching of the mattress or upholstery, particularly in such situations where the structure is attached around its edges and is not provided with an overall backing and other variations in the forming of the structure may be carried out without departing from the scope of the invention.

I claim:

1. A method of forming resilient upholstery consisting at least in part of thermoplastic organic plastic expanded by having pores therein and having two opposite faces, comprising the steps of compressing resilient expanded plastic over at least a substantial part of the area of the upholstery to close up the pores therein and reduce the thickness, applying heat over relatively small portions of the compressed area to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces.

2. A method of forming resilient upholstery consisting at least in part of thermoplastic organic plastic expanded by having pores therein and having edge portions of unexpanded plastic and two opposite faces, comprising the steps of compressing resilient expanded plastic over at least a substantial part of the area of the upholstery to close up the pores therein and reduce the thickness, applying heat over relatively small portions of the compressed area including at least those portions of the plastic which will form the edge portions of the upholstery to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces

tension in a direction parallel with said face or faces while the plastic remote from said face or faces is stressed by being compressed parallel with said face or faces.

3. A method of forming resilient upholstery consisting at least in part of thermoplastic organic plastic expanded by having pores therein and having edge portions of unexpanded plastic and two opposite faces, comprising the steps of compressing resilient expanded plastic over at least a substantial part of the area of the upholstery to close up the pores therein and reduce the thickness, applying heat over relatively small portions of the compressed area including at least those portions of the plastic which will form the edge portions of the upholstery to render them plastic and remove the pores therefrom, allowing the heated portions to cool and solidify, releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces, and trimming away surplus plastic from outside the boundary defined by said edge portions.

4. A method of forming resilient upholstery consisting at least in part of thermoplastic organic plastic expanded by having pores therein and having edge portions of unexpanded plastic and two opposite faces, comprising the steps of compressing resilient expanded plastic over at least a substantial part of the area of the upholstery to close up the pores therein and reduce the thickness, applying heat over relatively small portions of the compressed area comprising those portions of the plastic which will form the edge portions of the upholstery and anchor points within the main body of the upholstery to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces.

5. A method of forming resilient upholstery consisting at least in part of thermoplastic organic plastic expanded by having pores therein and having edge portions of unexpanded plastic and two opposite faces, comprising the steps of compressing resilient expanded plastic over at least a substantial part of the area of the upholstery to close up the pores therein and reduce the thickness, applying heat over relatively small portions of the compressed area comprising those portions of the plastic which will form the edge portions of the upholstery and anchor lines within the main body of the upholstery to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces.

6. A method of forming resilient upholstery consisting in part of thermoplastic organic plastic expanded by having pores therein and having two opposite faces, comprising the steps of compressing resilient expanded plastic in the form of a mass of shreds and granules of plastic sandwiched between two or more sheets of plastic forming the said faces, over at least a substantial part

of the area of the upholstery to close up the pores therein and reduce the thickness, applying heat over relatively small portions of the compressed area to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces.

7. A method of forming resilient upholstery consisting at least in part of thermoplastic organic plastic expanded by having pores therein and having two opposite faces, comprising the steps of compressing expanded plastic in the form of two outer sheets of expanded plastic having one degree of resilience and a sheet of expanded plastic having a different resilience sandwiched therebetween over at least a substantial part of the area of the upholstery to close up the pores therein and reduce the thickness, applying heat over relatively small portions of the compressed area to render them plastic and remove the pores therefrom, allowing the heated portions to cool and solidify and releasing the compression to allow the pores of the main body of the upholstery to open and the main body to return to substantially its original thickness, whereby the plastic adjacent at least one of the opposite faces of the upholstery is stressed by being under tension in a direction parallel with said face or faces while the plastic remote from said face or faces is stressed by being compressed parallel with said face or faces.
